Kelson W. Howard*

UNITED STATES PATENT OFFICE.

MOSES E. SHACKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

COUNTER-PINKING MACHINE.

1,365,794.

Specification of Letters Patent. Patented Jan. 18, 1921.

Application filed June 23, 1919. Serial No. 306,143.

To all whom it may concern:

Be it known that I, MOSES E. SHACKLEY, a citizen of the United States, residing at Lynn, in the county of Essex and State of 5 Massachusetts, have invented certain Improvements in Counter-Pinking Machines, of which the following description, in connection with the accompanying drawings, is a specification, like reference characters on 10 the drawings indicating like parts in the several figures.

This invention relates to cutting machines and is herein illustrated as embodied in a machine for pinking the edge of a blank, 15 such as a counter, for use in the manufacture of boots and shoes.

In the lasting of a shoe the margin of the rear portion of the upper, including the margin of the counter, is wiped over the margin of the heel portion of the insole. 20 Because of the curve of the upper at this point a certain amount of surplus material results, and the thicker the counter the more the surplus material. In order to facilitate the 25 wiping operation and to get rid of a certain amount of the surplus material, it is desirable at times, particularly when very heavy counters are being used, to pink the lower edge of the counter; and the general object 30 of the present invention is to provide a machine for performing this and similar operations.

It is desirable that the pinking should be produced not along the entire lower edge of 35 the counter, but only along the middle portion of the edge where the curvature of the counter when in place in the shoe is sharp, and that the location of the pinking cuts be accurate and uniform. Accordingly the 40 illustrative machine is provided with a cutting bed, a pinking cutter, and means for positioning a blank widthwise and lengthwise to cause the pinking of the selected edge to be done accurately. In the illustrative machine the positioning means takes the form of end gages which are adjustable in unison equally in opposite directions and a back gage which is adjustable widthwise of the blank, the latter gage contacting with 45 the blank at two separated points located on opposite sides of the cutter. With such a machine blanks of different shapes and sizes 50 may be pinked with accuracy and rapidity. These and other features of the invention,

including certain details of construction and 55 combinations of parts, will be described as embodied in an illustrative machine and pointed out in the appended claims.

Referring now to the accompanying drawings,— 60

Figure 1 is an elevation of a machine in which the present invention is embodied;

Fig. 2 is a plan view of the machine, and

Fig. 3 is an elevation of a counter which has been pinked on the machine. 65

Vertically slidable in bearings in the frame 5 of the machine is a rod 7 the lower end of which is pivoted at 9 to a lever 11, said lever being connected at one end by a pin-and-slot connection 13 to the frame of 70 the machine and at the opposite end by a pivot 15 to a treadle rod 17. This rod is normally held up by a spring (not shown) but may be pulled down into the position shown by depressing the treadle. Fast to 75 the upper portion of the rod is a carrier 19 having at its rear portion a yoke 21 which embraces a vertical guide 23 formed on the frame of the machine, and mounted in the carrier are a plurality of pinking tools 24, 80 three being shown arranged side by side. By referring to Fig. 2 it will be seen that the middle tool has formed on its lower end one pinking cutter and that, of the end tools, each has formed thereon two pinking cutters. The stem of each tool has at its upper end a cylindrical portion which fits in a bore 85 in the carrier 19 and is held in position by a set screw 25. Threaded into the carrier above the tools are three adjusting screws 90 27 having lock nuts 29 thereon. With this construction the tools 24 may be adjusted independently and held firmly in adjusted position.

Located beneath the tools is a cutting bed 95 31 the face of which may be of brass or other suitable material, the counter or other blank being supported by this bed during the pinking operation as indicated in Figs. 1 and 2. In order to position the blank lengthwise 100 upon the bed, there are provided two end gages 33 through which is threaded a right-and-left screw 35 which is rotatable in bearings in the frame of the machine but held from longitudinal movement. Each end 105 gage has at its rear end a yoke 37 which embraces a guide 39, this construction serving to guide the gages and to prevent them from

turning. In order to position the blank widthwise upon the bed there is provided a back gage 41 which slides forward and back in a dove-tailed groove cut in the frame of the machine. An adjusting screw 43, held from movement with respect to the frame of the machine, is threaded into this back gage; and a set screw 45, passing freely through a slot in the gage and threaded into the frame, 10 furnishes means for holding the gage in adjusted position. This gage has two downwardly extending fingers 141 arranged on opposite sides of the pinking cutters and adapted thus to engage the edge of the blank 15 at two separate localities equidistant from the cutters. A gage of this shape is particularly adapted for counters and similar blanks having more or less pointed ends and curved edges. By making the back gage 20 with two separated fingers, the blank is held from turning about a vertical axis, and at the same time blanks the edges of which have differently curved contours may readily be positioned.

25 In the operation of the machine, the gages are first set by placing a counter upon the bed, turning the screw 35 until the end gages 33 contact with the ends of the counter, and turning the screw 43 until the counter is 30 properly located widthwise. Thereafter all the counters of that size and style may be rapidly pined by presenting them one at a time and manipulating the treadle-rod 17. When a lot of counters of a different shape 35 or size are to be operated upon, the gages are again adjusted.

Although the invention has been set forth as embodied in a particular machine, it should be understood that the invention is 40 not limited in the scope of its application to the particular machine which has been shown and described.

Having thus described my invention, what I claim as new and desire to secure by Letters Patent of the United States is:

1. A machine of the class described, having in combination, a cutting bed, a cutter, means for causing relative movement of approach between the bed and cutter, and 45 means for positioning a blank on the bed, said positioning means comprising gages arranged to contact with the ends of the blank, and a gage arranged to contact with an intermediate portion of the blank, means whereby the end gages may be adjusted relatively in opposite directions, and means whereby the other gage may be adjusted in a path at an angle to that of the end gages.

2. A machine of the class described, having in combination, a cutting bed, a cutter, means for causing relative movement of approach between the bed and cutter, and means for positioning a blank on the bed, said last-named means comprising end gages, 65 means for adjusting them simultaneously

and equally in opposite directions, a back gage shaped to contact with the blank at separated points, and means for adjusting the back gage in a path at an angle to that of the end gages.

70

3. A machine of the class described, having in combination, a cutting bed, a cutter, means for causing relative movement of approach between the bed and cutter, and means for positioning a blank on the bed, 75 said positioning means comprising end gages, a right and left screw threaded through said gages, means for holding the gages substantially in alinement during the movement of them produced by turning the 80 screw, a back gage shaped to engage the blank at separated points, and means whereby the back gage may be adjusted with respect to the end gages.

85

4. A machine of the class described, having in combination, a cutting bed, a cutter, means for causing relative movement of approach between the bed and cutter, and means for positioning a blank on the bed, 90 said positioning means comprising a guide extending longitudinally of the bed, end gages slidably engaged therewith, a right and left screw threaded through said gages, a second guide extending transversely of the bed, a back gage slidably engaged therewith, and means for advancing and retracting 95 the back gage.

5.

5. A machine of the class described, having in combination, a cutting bed, a reciprocating carrier, a plurality of pinking tools 100 mounted in the carrier, and means for positioning a stiffener blank on the bed, said positioning means comprising end gages adjustable in unison equally in opposite directions to locate the blank lengthwise substantially medially of the tools, and a back gage 105 adjustable to cause the cutters to pink the edge of the blank.

6.

6. A machine of the class described, having in combination, a cutting bed, a reciprocating carrier, a plurality of pinking tools 110 mounted in the carrier, means whereby the tools may be adjusted toward and from the bed independently of one another, and means for positioning a stiffener blank on 115 the bed, said positioning means comprising end gages adjustable in unison equally in opposite directions to locate the blank lengthwise substantially medially of the tools, and a back gage adjustable to cause 120 the cutters to pink the edge of the blank.

7.

7. A machine of the class described, having in combination, a cutting bed, a reciprocating carrier, a plurality of pinking tools 125 mounted in the carrier, and means for positioning a stiffener blank on the bed, said positioning means comprising end gages adjustable in unison equally in opposite directions to locate the blank lengthwise substantially medially of the tools, and a back 130

gage comprising two spaced fingers located on opposite sides of the tools adjustable to cause the cutters to pink the edge of the blank.

5 8. A counter pinking machine, having in combination, a cutting bed, a pinking cutter, a gage for positioning a counter widthwise and a pair of gages for positioning the counter lengthwise with respect to the cutter, mechanism for moving the gages of said pair equally in opposite directions and means for causing relative movement of approach between the bed and cutter to pink the edge of the counter.

10 15 9. A counter pinking machine, having in

combination, a cutting bed, a plurality of pinking cutters, and means for positioning a counter on the bed, said positioning means comprising end gages adjustable in unison equally in opposite directions and maintained always substantially equidistant from the cutters and a back gage adjustable at an angle to the direction of adjustment of the end gages, said back gage having two fingers also substantially equidistant from the cutters. 20 25

In testimony whereof I have signed my name to this specification.

MOSES E. SHACKLEY.
